UNITED STATES PATENT OFFICE.

ADRIEN GREDELUE, OF NEW YORK, N. Y.

DESIGN FOR A DRINKING VESSEL.

41,341.

Specification for Design.

Patented May 2, 1911.

Application filed February 17, 1911. Serial No. 609,269. Term of patent 14 years.

To all whom it may concern:

Be it known that I, ADRIEN GREDELUE, a citizen of the Republic of France, residing at New York city, county of New York, State of New York, have invented a new, original, and ornamental Design for Drinking Vessels, of which the following is a specification, reference being had to the accompanying drawing, forming part thereof.

The figure is a view in elevation of a drinking vessel, showing my new design.

I claim:

The ornamental design for a drinking vessel, as shown.

A. GREDELUE.
